(57) **CLAIM**

The ornamental design for a band, as shown and described herein.

DESCRIPTION

FIG. 1 is a front perspective view of one embodiment of a band of my new design, that portion of the band shown in phantom is not part of the design sought to be patented and is provided for environmental purposes only.

FIG. 2 is a top plan view of the band of my new design illustrated in FIG. 1, that portion of the band shown in phantom is not part of the design sought to be patented and is provided for environmental purposes only. The bottom view being a mirror image of the top view shown.

FIG. 3 is a front plan view of the band of my new design illustrated in FIG. 1, that portion of the band shown in phantom is not part of the design sought to be patented and is provided for environmental purposes only,

FIG. 4 is a rear plan view of the band of my new design illustrated in FIG. 1, that portion of the band shown in phantom is not part of the design sought to be patented and is provided for environmental purposes only; and,

FIG. 5 is a left side plan view of the band of my new design illustrated in FIG. 1, that portion of the band shown in phantom is not part of the design sought to be patented and is provided for environmental purposes only. The right side view being a mirror image of the left side view shown.
